FOLDING CHAIR

Clarence A. Best, New Albany, Ind.

Application January 10, 1936, Serial No. 58,445

2 Claims. (Cl. 155—117)

My invention relates to improvements in folding chairs of the type known as lawn chairs.

The main object of my invention is to provide a chair of this kind in a simple, inexpensive, durable and convenient form.

Another object is to provide a chair employing a minimum of parts comprising a back, arm rests pivoted at one end to the back at each side, legs pivotally mounted midway of their ends on the back, means for readily and adjustably connecting the free ends of the arm rests and the intended upper ends of the legs, a seat pivotally mounted at its rear edge to the back, and seat supporting legs pivotally mounted beneath the free edge of the seat.

Another object is to provide a chair of this kind including a writing desk or leaf hinged to one arm rest, a magazine rack behind the said back and receptacles for an ash tray and other smokers' articles on one arm rest.

A further object is to provide a chair of this kind having novel and handy means for mounting and supporting a lawn or beach umbrella over the chair.

With these and other objects in view the invention resides in the novel construction and arrangement of parts as hereinafter fully set forth and claimed, reference being had to the accompanying drawing wherein:

Figure 1 is a perspective view of my improved chair ready for use.

Figure 2 is a fragmental enlarged side elevation.

Figure 3 is an enlarged edge view of the writing desk or leaf and the adjacent arm rest and leg.

Figure 4 is a fragmental perspective view of the chair back viewing the same from the rear and showing the magazine rack thereon.

Figure 5 is an enlarged fragmental perspective view of one leg showing the locking pin thereon.

Figure 6 is an enlarged perspective view of the leg lock.

In carrying out my invention I provide a back shown generally at 7 comprising spaced parallel sides 8 joined by cross pieces or bars 9 which in turn are spanned by slats or strips 10 arranged in any suitable pattern and parallel with the sides 8. These slats 10 extend the length of the back 7 terminating at their lower ends some distance above the lower ends of the side 8 as shown and the upper and lower cross bars 9 are fitted in recesses at 11 into the rear edges 55 of the sides 8 while the center bar 9 lies flat on

these edges thus giving a bowed shape to the back as formed by the slats.

Legs 12 are pivotally mounted intermediate their ends by bolts 13 on the sides 8 of the back 7 some distance below the slats 10 and may be 5 folded when not in use flat alongside the sides 8. Arm rests 14 are pivoted at their ends by bolts 15 to the sides 8 above the legs 12 and in such position that they may also fold up alongside these sides while clearing the legs 12 in their 10 folded positions. The legs 12 carry headed locking pins 16 on their upper ends and at spaced points below and near the free ends of each arm rest 14 locking means are provided each comprising an L-shaped bracket 17 screw fastened 15 to the arm rest and having a downwardly opening notch 18 adapted to receive the pin 16 on the leg. Thus by entering the pins 16 in the notches 18 the legs 12 may be secured in a position forming "crosses" with the sides 8 of the 20 back 7 to support the back in a rearwardly inclining position as shown. By changing the pins 16 from the brackets 17 nearest the outer ends 25 of the arm rests 14 to the brackets inwardly thereof the pivotal points 13 of the legs are elevated to a higher point and the inclination of the back 7 reduced in well known manner. To lock the pins 16 in the proper notches 18 each bracket 17 has a lock lever 19 pivoted at 20 above the notches 18 and having a laterally opening notch 21 near its free end adapted to also engage the pin and prevent pulling the bracket from the same as will be understood. These levers 19 have ears 22 extended outward from their free ends as a convenience in swinging them 30 into or out of engagement with the locking pins. The arm rests 14 when locked to the legs 12 are supported in substantially horizontal position 35 while acting at the same time as supports for the legs.

A seat 23 of rectangular form is provided and comprises spaced and parallel side bars 24 secured together by spaced cross slats 25 as shown and this seat is hinged to the back 7 at one edge by pivotally mounting the ends of the side 45 bars 24 inside the sides 8 on the leg mounting bolts 13. Thus the seat when not in use may be folded up flat against the back 7. Seat supporting legs 26 are pivoted at their upper ends by bolts 27 within the outer ends of the side 50 bars 24 and these legs may then fold back flat alongside these side bars when the seat is folded. The legs 26 are joined by a cross bar 28 and when opened to support the seat 23 as shown 55 are held in vertical position by articulated arms

29 pivotally mounted at their ends 30 to the side bars 24 and the legs and joined centrally by a rule joint 31 in well known manner.

From the foregoing it will be evident that the 5 chair may be folded very compactly when not in use and when opened will provide a comfortable and sturdy chair. The "six point" bearing by the sides 8, legs 12 and legs 26 especially conduces to a strong and rigid support for the chair.

10 One arm rest 14 has recesses 32 to receive cigarettes, matches and ash trays and the like. A writing desk or leaf 33 is also hinged by one edge at 34 to the inner edge 35 of this arm rest and when swung upward to a horizontal position 15 serves as a convenient plane surface for writing and like operations. A support arm 36 is pivotally mounted at 37 to one leaf of a strap hinge 33 mounted below the leaf 33 near its outer edge and when the leaf is raised the lower end of the arm 20 36 drops into an eye 39 on the adjacent leg 12 rigidly supporting the leaf. When not in use the arm 36 is swung on the pivot 37 to lie flat against the leaf and the leaf is dropped down inside the arm rest 14.

25 A magazine rack is provided on the back 7 by a strip 40 secured along the center cross bar 9 and a loop 41 secured to the upper cross bar 9 as shown in Figure 4. A spring clip 42 is secured to one arm rest 14 near its pivot 15 and has 30 spring set normally converging outwardly projecting jaws 43. In vertical alignment below jaws 43 an eye 44 is screwed into the inner side of the leg 12 near its lower end. A lawn or beach umbrella (not shown) may have its staff dropped 35 through the eye 44 and slipped between the jaws 43 to support the umbrella over the chair.

While I have herein set forth a certain preferred embodiment of my invention, it is understood that I may vary from the same in minor structural 40 details, so as best to construct a practical device for the purpose intended, not departing from the spirit of the invention, and within the scope of the appended claims.

I claim:

45 1. In a foldable chair combination, a back having a pair of forwardly extended legs at the

sides thereof, a pair of rearwardly extended legs medially pivoted by pivot pins to the outer sides of the forwardly extended legs, a seat pivotally connected at its rear portion to the inner sides of the forwardly extended legs by means of the pivot pins connecting the legs of the assembly, the seat being foldable upwardly against the back, supports foldably connected with the forward end of the seat for maintaining the seat in horizontal position when opened, arms pivoted at their rear ends to the outer sides of the back and adjustably connected at their forward ends with the upper ends of the rearwardly extended legs, a writing leaf hinged to the inside edge of one of the arms and arranged for opening horizontally inward over the seat for use, and for folding downward into the space between the adjacent outer side of the seat and the inner side of the adjacent rearwardly extended leg, out of the way to allow the seat to pass upwardly for 20 folding against the back, and means for holding the writing leaf in horizontal position.

2. In a foldable seat combination including a back having a pair of forwardly extended legs at the sides thereof and a pair of rearwardly extended legs medially pivoted to the forwardly extended legs at the outer sides thereof, a seat pivotally connected at its rear portion to the inner sides of the forwardly extended legs, means to support the seat in horizontal position, the 25 seat being foldable upwardly against the back, and side arms pivoted at their rear ends to the outer sides of the back and adjustably connected at their forward ends with the upper ends of the rearwardly extended legs, a writing leaf hinged to the inner edge of one of the arms and arranged for opening horizontally inward over the seat for use and for folding downwardly into the space formed between the adjacent outer side of the seat and the adjacent inner side of the rearwardly extended legs and thus out of the way to allow the seat to fold upwardly against the back, and means for holding the writing leaf in horizontal position.

CLARENCE A. BEST.
